UNITED STATES PATENT OFFICE

171,626

MOBILE CRANE

Glenn W. Way, Delaware, Ohio

Application May 29, 1953, Serial No. 25,239

Term of patent 14 years

(Cl. D14—3)

To all whom it may concern:

Be it known that I, Glenn W. Way, a citizen of the United States, residing at Delaware, State of Ohio, have invented a new, original, and ornamental Design for a Mobile Crane, of which the following is a specification, reference being had to the accompanying drawing, forming a part thereof.

Figure 1 is a side elevational view of a mobile crane showing my new design;

Figure 2 is a front elevational view thereof with the crane boom in an offset position; and

Figure 3 is a rear perspective view thereof.

I claim:

The ornamental design for a mobile crane, as shown.

GLENN W. WAY.
